UNITED STATES PATENT OFFICE.

ARTIMUS W. SHIDLER, OF FARMINGTON, NEW MEXICO.

STEAM-GENERATOR.

1,280,318.

Specification of Letters Patent.

Patented Oct. 1, 1918.

Application filed May 6, 1916. Serial No. 95,953.

To all whom it may concern:

Be it known that I, ARTIMUS W. SHIDLER, a citizen of the United States, residing at Farmington, in the county of San Juan and 5 State of New Mexico, have invented certain new and useful Improvements in Steam-Generators; and I do hereby declare the following to be a full, clear, and exact description of the invention, such as will enable others skilled in the art to which it 10 pertains to make and use the same.

This invention relates to a device which is particularly designed for removing snow from railroads, streets, street car tracks or 15 the like and the primary object of the invention is to provide a snow removing device as specified which utilizes steam for melting the snow which materially decreases the cost of removing snow from city streets, 20 railroad tracks or the like in that the cost of hauling the snow is eliminated.

A further object of this invention is to provide a device as specified which is mounted upon an ordinary flat car and includes 25 a boiler structure having a plurality of pipes, through which water passes, for conversion into steam and to mount fire boxes within the boiler structure for converting the water into steam during its passage 30 through the pipes.

A further object is to provide a flexible hose which is connected to the steam chest of the device and has a nozzle on its outer end for directing the steam from the steam 35 chest against the snow for the purpose of melting the latter.

A further object of this invention is to provide a pump structure for forcing water into the boiler tubes and also to provide a 40 blower structure for increasing the action of the fire within the fire boxes.

With the foregoing and other objects in view this invention consists in such novel features of construction, combination and 45 arrangement of parts as will be hereinafter more fully described, illustrated in the accompanying drawings and claimed.

In describing the invention in detail reference will be had to the accompanying drawings wherein like characters designate like and corresponding parts throughout the several views, and in which:—

Figure 1 is a side elevation of the improved snow removing device.

55 Fig. 2 is a top plan view of this snow removing device.

Fig. 3 is an end view of the snow removing device.

Fig. 4 is a cross section through the device, and

60

Fig. 5 is a detail view of the nozzle.

Referring more particularly to the drawings, 1 designates a portable flat car of any ordinary construction upon which the improved snow melting device is mounted. The 65 snow melting device which is generically indicated by the numeral 2, includes a casing having an open bottom, which is built up of pipes extending longitudinally of the casing and having their ends connected by the ordinary type of U-couplings indicated at 3. The pipes 4 which form the upper portion of the casing 2 extend across the ends of the casing as clearly shown in Fig. 3 of the drawings so that they form the entire 70 upper portion of the casing. The ends of the lower portion of the casing are formed by sheet metal plates 5 which are provided with doors 6 to permit of the throwing of fuel, such as coal or the like interiorly of 80 the casing. The bottom of the casing is formed of pipes 7 which form grate bars and also water or liquid containers. A pump structure 8 of any ordinary construction is operatively connected through the 85 medium of a short length of pipe 9 to the series of pipes of which the casing is formed, for forcing water into the series or system of pipes. A water feed pipe 10 communicates with the pump 8. The casing has a 90 steam chest 11 carried thereby, at the top of the casing into which the steam passes from the series or system of pipes. It is preferable to have a lining indicated at 12 positioned within the casing 2 for preventing the action of the fire therein from being applied directly to the pipe. A safety or pop-off valve structure 13 is carried by the steam chest 11. A water gage 14 is connected in the series of pipes for indicating 95 the quantity of water therein.

A blower 15 is provided, the outlet 16 of which communicates with a pipe 17. The pipe 17 extends longitudinally along one side of the casing 2 and has communication 105 with transversely extending outlet pipes 17' which guides the air blast from the fan or blower 15 upwardly into the fire boxes, for increasing the combustion of the fuel therein. A fire box is positioned at each end of the 110 casing.

An outlet pipe 20 is carried by the for-

- ward end of the steam chest 11 and it has a valve structure 21 carried thereby for controlling the passage of steam out of the chest and through the flexible hose 22 which is connected to the pipe 20. A nozzle 23 is mounted upon the outlet end of the flexible hose 22 and it is preferably provided with an elongated slot 24 out of which the steam egresses, for causing the steam to engage the snow in a flat relatively broad stream. Coal or fuel retaining hoppers or boxes 24 are carried by the car 1 and are positioned so that the fuel may be conveniently thrown therefrom into the fire boxes.
- 16 A smoke stack 25 of any suitable construction is provided for permitting of the escape of the products of combustion from the fire boxes.
- 18 In the operation of the improved device 20 for melting snow from railways, streets or the like, water is fed to the series or system of pipes by the action of the pump 8 and the fire built within the fire boxes at each 25 end of the casing will convert the water into steam which steam will pass upwardly through the series of pipes into the steam chest 11. The outlet of the steam from the steam chest 11 is controlled by the operation of the valve and when it is desired 30 to melt the snow, the valve is opened which permits the steam to pass outwardly through the hose 22 and the nozzle 23. The nozzle 23 is manually operated or moved about so as to guide the issuing steam on the snow for the 35 purpose of melting the latter and causing it to run off the track or street in liquid form thereby eliminating the inconvenience of loading and hauling the snow.
- 38 From the foregoing description taken in 40 connection with the accompanying drawings,

the advantages of construction and of the method of operation of the improved device for melting snow from railroads, streets, etc., will be readily apparent to those skilled in the art to which this invention appertains, 45 and while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed. 50

What is claimed is:—

55 A device of the character set forth comprising a casing having an open bottom and ends, said casing having its top wall dome-shaped and provided with a longitudinally extending groove, a plurality of horizontally disposed pipes placed on the casing, series of pipes closing the upper half of the ends of said casing and connected in series with some of the horizontal pipes, a series of bottom pipes closing the bottom of said casing to 60 form a grate and connected in series with each other and to some of the horizontal pipes, plates closing the lower half of the ends of said casing and having fuel receiving openings to permit a fire to be built on the 65 bottom pipes from each end of the casing, and a steam dome located in the groove and connected to the series of horizontal pipes for receiving steam from the pipes.

In testimony whereof I affix my signature 70 in presence of two witnesses.

ARTIMUS W. SHIDLER.
